(57) **CLAIM**

The ornamental design for a DC switch disconnector, as shown and described.

DESCRIPTION

FIG. 1 is a front side perspective view of a DC switch disconnector.

FIG. 2 is a top side view of the DC switch disconnector shown in FIG. 1.

FIG. 3 is a bottom side view of the DC switch disconnector shown in FIG. 1.

FIG. 4 is a left side view of the DC switch disconnector shown in FIG. 1.

FIG. 5 is a right side view of the DC switch disconnector shown in FIG. 1.

FIG. 6 is a rear side view of the DC switch disconnector shown in FIG. 1; and,

FIG. 7 is a front side view of the DC switch disconnector shown in FIG. 1.

The broken lines in the drawings illustrate portions of the DC switch disconnector that form no part of the claimed design.
